UNITED STATES PATENT OFFICE.

LÉON DUFOUR, OF GENEVA, SWITZERLAND.

INTERNAL-COMBUSTION ENGINE.

1,241,833.

Specification of Letters Patent.

Patented Oct. 2, 1917.

Application filed April 6, 1917. Serial No. 160,337.

To all whom it may concern:

Be it known that I, LÉON DUFOUR, engineer, a citizen of Switzerland, residing at Geneva, Canton of Geneva, in the Confederation of Switzerland, have invented certain new and useful Improvements in Internal-Combustion Engines, of which the following is a specification.

In one of the well-known systems of valveless combustion engines the distribution within each cylinder is effected by means of a distributing sleeve moving inside of the cylinder and provided with a simultaneous rotary and sliding movement. This combined movement is obtained in the said engines by means of a cross-bar connected with each sleeve and swung round by two parallel and similar cranks attached at its ends and keyed to two parallel counter-shafts which revolve at half the speed of the main-shaft.

The connection between cross-bar and sleeve may be made in the manner as described in the Swiss Letters Patent No. 61999 or the French Letters Patent No. 464440 granted to the same inventor.

If valveless motors of this system have to be constructed with eight or twelve convergent cylinders by forming two groups of motors of four or six cylinders each the rotary sliding movement of the sleeves would be obtained by four parallel counter-shafts or by two shafts for each group of the cylinders located in the same inclined plane.

The present invention consists in reducing to three the number of counter-shafts needed by substituting for the two middle shafts located between the two groups of cylinders one single shaft fitted with all the cranks for working the inside ends of the cross-bars of sleeves. There results from this arrangement a saving by simplifying the constructive parts and also some reduction in width of the space occupied by the machine.

In the drawing:

Figure 1 is a diagrammatic section illustrating a pair of engine cylinders to which the present invention is applied.

Fig. 2 is a plan of the crank shaft employed intermediate of the engine cylinders.

Fig. 3 is a view similar to Fig. 1 illustrating another form of the invention.

Fig. 4 is a plan of the crank shaft employed between the cylinders in the form of the invention shown in Fig. 3, and

Fig. 5 is a partial sectional plan showing the manner in which the distributing sleeves are connected to the cross bars.

Referring particularly to Fig. 1 a^1 and a^2 are the two cylinders of the first pair of cylinders, b^1 and b^2 the distributing sleeves, d^1 , d^2 the cross-bars attached to these sleeves at the points c^1 , c^2 . e^1 , e^2 and e^3 are the three counter-shafts fitted with the cranks g^1 , g^2 , g^3 , g^4 and crank pins k^1 , k^2 , k^3 , k^4 . o is the main shaft, f the crank pin for working the connecting rods l^1 , l^2 attached to the pistons h^1 , h^2 . α is the angle between the two axes of cylinders.

The distributing sleeve in each cylinder may be provided with a bifurcated extension or lug b^3 as indicated in Fig. 5 adapted to receive a pin d^3 in the corresponding cross bar and to be received in a recess provided for the ends of the bifurcated extension in this cross bar in order as will be understood, to not only impart a reciprocating motion from the cross bar to the sleeve, but also to impart a partial rotary motion to the sleeve within the cylinder. It will be further understood that the connection between the distributing sleeve and the corresponding cross bar may be made in the manner hereinbefore described or in either of the ways shown and described in Letters Patent No. 1,132,247 granted to me March 16, 1915 for an improvement in explosive engines.

The working is as follows:

Starting from the position of the upper dead point of piston h^2 , this position will also correspond to the upper dead point position of sleeve b^2 , that is to a position where the cranks g^3 , g^4 are parallel to the axis of cylinder a^2 and where the crank pins k^3 , k^4 are turned upward. The corresponding position of the crank pins k^1 , k^2 is the one shown in Fig. 1 of the drawing, that is to say a position turned forward with regard to the crank pins k^3 , k^4 at an angle

equal to $\frac{x}{2}$ (the direction of turning of shaft o being clockwise.) Indeed as shafts e^1 , e^2 and e^3 are turning in the same direction as the main shaft o but at half the speed the crank pins k^1 , k^2 will have turned at an angle $\frac{x}{2}$ while the pin f will have turned at an angle α . In this new position the upper dead point will be reached by sleeve b , and cylinder a^1 . It will then be noticed that

owing to the shown arrangement of parts the upper dead point of the pistons h^1 , h^2 will alternatively correspond at each revolution of the main shaft with the upper dead point and the lower dead point of the respective sleeves.

Referring to Fig. 2, which is a plan of the counter-shaft e^1 showing the eight crank pins in their respective positions in an eight cylinder motor, it will be seen that for each cylinder the upper dead point of the piston alternatively coincides at each revolution of the motor with the upper and lower dead points of the respective sleeve.

Fig. 3 shows a second working form of the distributing gear wherein for the two crank pins h^1 , h^4 one single pin k has been substituted, which pin is in an intermediate position, as shown in the drawing, a position

which is turned forwardly at an angle $\frac{x}{4}$ with regard to the position of pin k^4 and turned backward at the same angle with regard to the position of pin k^1 . To this pin k the interior ends of the cross-bars d^1 and d^2 of the sleeves b^1 and b^2 are attached. As compared to the positions of sleeves b^1 and b^2 in the preceding example the position of sleeve b^2 will be changed here in a forward sense, while the position of sleeve b^1 is changed in a backward sense; but these changes of position are so small that their influence on the distribution can easily be compensated by a suitable shape of the port-holes.

The working of this form of gear is the same as the working of the preceding example if the intermediate position of the crank-pins is taken into account by a suitable form of port-holes.

In this second working form the number

of cranks of the central counter shaft is diminished to one half which will simplify and cheapen the construction of such motors.

The two working forms shown of a distributing gear may just as well be employed also for motors with twelve convergent cylinders.

I claim as my invention:

1. In an internal combustion engine the combination with a plurality of cylinders arranged in pairs with the axes of each pair of cylinders at an angle to each other, a distributing sleeve movable in each cylinder and a cross-bar connected to each sleeve, of a crank shaft intermediate the pairs of cylinders and to which the adjacent ends of the cross bars of the sleeves of each pair of cylinders are connected, and crank shafts to which the distant ends of the cross bars of each pair of cylinders are connected.

2. In an internal combustion engine the combination with a plurality of cylinders arranged in pairs with the axes of the cylinders at an angle to each other, a distributing sleeve movable in each cylinder, a piston within each distributing sleeve, a drive shaft and connections between the drive shaft and the pistons, of a single crank shaft intermediate of the pairs of cylinders and to which the adjacent ends of the cross bars of the sleeves of each pair of cylinders are connected, and crank shafts to which the other or distant ends of the cross bars for each pair of cylinders are connected.

In testimony whereof I have affixed my signature in presence of two witnesses.

LÉON DUFOUR.
